UNITED STATES PATENT OFFICE.

ELMER O. BEARDSLEY, OF CHICAGO, AND WALTER F. PIPER, OF OAK PARK, ILLINOIS.

METHOD OF MAKING MOLDS FOR STEEL CASTINGS.

1,309,834.

Specification of Letters Patent.

Patented July 15, 1919.

Application filed January 29, 1919. Serial No. 273,862.

To all whom it may concern:

Be it known that we, ELMER O. BEARDSLEY and WALTER F. PIPER, both citizens of the United States, and residents of Chicago, in the county of Cook and State of Illinois, and Oak Park, in the county of Cook and State of Illinois, respectively, have invented certain new and useful Improvements in Methods of Making Molds for Steel Castings, of which the following is a full, clear, and exact description.

The invention relates to making molds for steel castings.

It has heretofore been proposed to make sand molds for founding by dropping wads of sand or projecting them forcibly into a mold, but, so far as we are aware, no apparatus or method of this type heretofore known has ever been adapted to produce good molds adapted for making steel castings.

The object of the present invention is to provide an improved method of making molds for steel castings by which the work of filling the molds is greatly facilitated and the cost of production greatly reduced, as well as effecting a very important saving in time consumed in making and uniformity of quality of the mold so that wastage in or defective castings will be avoided.

In practice, we have discovered that a sand mold which is adapted for making steel castings can be formed by projecting the sand into the molds if it is done with the requisite regularity and force to sufficiently and uniformly densify the molding material in the flasks.

The invention consists in the several novel features hereinafter set forth and more particularly defined by claims at the conclusion hereof.

Apparatus that is adapted for the practice of the present method is shown in the accompanying drawings in which; Figure 1 is a side elevation of molding apparatus embodying the invention. Fig. 2 is a plan. Fig. 3 is a vertical longitudinal section. Fig. 3^a is a section taken on line 3^a—3^a of Fig. 3. Fig. 3^b is a detail of the upper conveyor and riddle operating mechanism. Fig. 4 is a section taken on line 4—4 of Fig. 3. Fig. 5 is a plan of the ramming head. Fig. 6 is a vertical axial section of the ramming head. Fig. 7 is a perspective of the rotor. Fig. 8 is a section taken on line 8—8

of Fig. 6. Fig. 9 is a section through the protective housing taken on line 9—9 of Fig. 8.

An apparatus adapted for practising the improved method for making steel castings may comprise a mast 10 which is provided at its upper end with a post 11 on which is journaled for horizontal rotation, a tubular jib 12 which has a socket 13 around the post 11. Anti-friction bearings 13' are provided to permit free and easy lateral movement of the jib. An arm 14 is pivoted to the distal end of the jib so that it and the ramming head sustained thereby can be swung horizontally, relatively to the jib. The pivotal connection between the arm and the jib consists of a hollow bracket 15 and a post 16 which is fixed to the jib 12 and mounted in anti-friction bearings 17 in said bracket. The casing 20 of an electric motor 21 is bolted, as at 22, to one side of the bracket 15, and arm 14 comprises a hollow sleeve 23 bolted to one side of the casing 20 and supports the ramming head and serves also as an inclosure for the shaft 24 between the electric motor 21 and the rotor of the ramming head. This shaft is mounted in a bearing 25 in the outer end of the sleeve 23 and serves as a bearing for the outer end of said shaft. The rotor for the sand for filling the flasks is fixed to the outer end of shaft 24.

A yoke comprising a hub 28 which is fixed and clamped, as at 27, to the sleeve 23, and arms 28' which have outwardly extending members 29 supports the casing or stator of the ramming head. This casing comprises an arcuate wall 30 and an outer side wall 31. This casing is secured to the yoke by bolt-and-slot connections 32 and set-screws 33 which are threaded to lugs 34.

A conveyer chute 37 containing a suitable sieve or riddle 38 is supported from the jib 12 by resilient bars 39 which have their ends respectively secured to the jib and to the chute. The inner end of chute 37 is adapted to receive sand from a suitable source of supply, such as a hopper 40 to which sand will be fed in any desired manner. The outer end of chute 37 discharges into the upper open end of an inclined chute 35 which is fixedly mounted on the arm 14, and is supported by bars 36 so that the relation between the arm, chute 35 and the ramming head remains fixed. The upper end of the chute 35 and the outer end of the chute 37

are disposed adjacent the axis about which the arm 14 swings, so that the relative movement of the chutes will maintain the discharge into the chute 35. The chute 37 and the riddle therein are vibrated by a pitman 41 which is pivoted to chute 37 and is operatively connected to an eccentric or wristpin 42 on a shaft 43 which is journaled in a bracket fixed to the upper end of the socket 13. An electric motor 44 is also mounted on said bracket and a pinion on the shaft of said motor meshes with a gear 46 which operates the shaft 43 and eccentric 42. This mechanism serves to shake the chute 37 and the riddle to cause it to disintegrate the sand and to discharge it regularly and continuously into the upper end of the chute 35 which is inclined sufficiently to cause the sand to flow lengthwise thereof and be discharged into the ramming head continuously by gravity. This construction exemplifies mechanism for feeding sand to the ramming head in which the chute on the outer arm is rigid therewith, so that no shaking mechanism for said chute is necessary.

The chute 35, as more clearly seen in Figs. 6 and 8, discharges into the open side of the ramming head. The centrifugal force has a tendency to suck the sand into the ramming head instead of spattering it outwardly by centrifugal force, as occurs when the sand is delivered to the periphery of the rotor. The rotor is adapted to receive the sand at the open side of the head and to project it downwardly into the mold. The rotor comprises a hub 50 and a cylindrical body 51, integral with the hub and secured to shaft 24, an inclined guide-flange 52 which is flared inwardly from the periphery of the inner side of the cylindrical body 51 and directs the sand onto the body 51. The guide-flange 52 is formed as a ring and is bolted to said body, as at 53. A curved outwardly extending bed 54 integral with the rotor body, is adapted to support the projector blade 55. Said blade is curved to fit the bed 54 and is provided with an inner side wall 56 which has a curved edge 57 and is adapted to function as a positive cut-off for the sand, so that as the rotor is revolving, the wall 56 will shear a portion of the sand issuing from the lower end of the chute from the sand in the chute. The rotor is counterweighted, as at 58, to balance the projector blade and its bed 54 and cause the rotor to run evenly at a very high speed. When the rotor is operated at a high speed, its curved base and centrifugal force cause the wad of sand which has been separated from the supply in the chute 35 to wedge and impact itself in the corner between the outer end of the plate and arcuate wall 30 of the casing, as shown in Fig. 8, so that

packed into a proper mass for projection into the mold. This construction of ramming head is peculiarly adapted for high speed operation, such as has been found necessary to form good molds for steel castings. 70

A protective housing 61, which is out of contact with the rotor, is suspended from the extensions 29 of the supporting yoke. It is desirable to have the head as open as possible to avoid atmospheric resistance to the high speed rotor and to have as short and rapid an operative stroke of the rammer blade as possible, since otherwise excessive power would be necessary to operate the rotor. For this purpose, the inner side of 80 the stator is open and the stator or casing begins at a point shortly before the projector-blade reaches the incoming sand stream from chute 35 and terminates at 60, where the wad will be discharged truly 85 downward into the mold. The wall 64 of the protective housing is disposed in off-set relation with respect to the discharge point 60. A three sided wear-plate 65 is secured in the housing. A handle 71 is secured to 90 the ramming head, whereby the operator can easily move the head laterally to distribute the projected sand to all portions of the mold.

In making molds for steel castings, the projector blade is driven so as to have a peripheral speed ranging approximately from 7000 to 8000 feet per minute. This speed may be attained, for example, by having a projector blade with its outer end 8½ inches from the axle of the rotor and driving the rotor at a speed ranging approximately from 1600 to 1800 revolutions per minute. This will impart to the wads of sand, which are sheared from the stream which is supplied to the projector at the rate of approximately ten cubic feet per minute, a velocity approximating 7000 to 8000 feet per minute, and will project 1600 to 1800 wads per minute into the flask. The action of the curved projector blade and centrifugal force, while the wads are in transit through the stator, will compact or densify the wads. The operator will manipulate the ramming head laterally to distribute the wads to fill all 110 portions of the flask. The movement of the head is truly lateral so the angle of delivery of the sand into the mold does not vary. This results in even density of the mold. 115

In practice, we have discovered that molds 120 made in accordance with the present method, will be adapted for steel castings, will be of uniform density and quality, and can be produced with much greater rapidity than has been possible by hand-filling. We have been able, with the present method, to fill and pack molds of good and uniform quality for steel castings eight times as fast as has been done by hand. 125

restricted to the precise practice set forth, and may be varied without departing from the spirit and scope of the invention.

Having thus described the invention, what we claim as new and desire to secure by Letters Patent, is:

1. That improvement in making molds for steel founding which consists in projecting wads of mold-material into a mold 10 at a velocity of not less than approximately 7000 feet per minute.

2. That improvement in making molds for steel founding which consists in projecting densified wads of material into a mold at a 15 velocity not less than approximately 7000 feet per minute.

3. That improvement in making molds for steel castings which consists in shearing transversely wads of sand from a substantially continuous stream and projecting 20 them into the molds at a velocity approximately not less than 7000 feet per minute.

4. That improvement in making molds for steel castings which consists in feeding sand in a stream to a projector at the rate of over 25 eight cubic feet per minute, shearing the sand into wads, and projecting the wads into a flask at a velocity of not less than approximately 7000 feet per minute.

ELMER O. BEARDSLEY,
WALTER F. PIPER.
